ADAPTER

Herbert F. Jermain, New York, N. Y., assignor
to Movietone, Inc., New York, N. Y., a corporation of New York

Application May 15, 1929, Serial No. 363,155

1 Claim. (Cl. 173—344)

This invention relates to a new and useful adapter for a radio vacuum tube base.

The amplifiers in commercial radio sets can be used for other purposes than amplifying radio signals. Application to phonograph record pick-up and sound attachments for talking moving picture projectors are specific examples. Successful utilization of a radio set amplifier for that purpose depends upon the adapter used in gaining an entrance to the amplifying system. If satisfactory results are to be obtained the radio frequency amplification system must be disconnected or uncoupled from the audio amplifying system.

15 The amplifiers of the previous art made no provision for accomplishing this result, but simply made connection to the grid circuit of the detector tube, leaving the grid lead from the foregoing stage intact.

20 It is, therefore, an object of my invention to provide an adapter that will make connection to the grid circuit of a vacuum tube of a radio set, and at the same time uncoupling the grid from the foregoing stages. This has an advantage of 25 eliminating any pick-up by the radio frequency stages and mixing the same with the input to the amplifier.

Further objects and advantages will be apparent with reference to the accompanying drawings in which:—

Figure 1 shows a complete adapter unit.

Figure 2 is a bottom view showing prong arrangement.

Figures 3 and 4 are sectional views showing details of construction.

Figure 5 is a fragmentary radio circuit showing the applicability of the adapter.

The cylindrical element 1 has one end enclosed 40 which forms the base supporting the prongs 5, 6, 7 and 8. On to these prongs are secured the receptacles 4 which receive the prongs of the radio tube.

It will be noted that the grid receptacle 9 in Figure 3 has no prong extending through the adapter base since it is an object of this device to eliminate the grid connection of the radio frequency stages.

45 Terminals 2 and 3 secured to the receptacle 9 and prong 5 respectively provide a means for the in-put to the amplifier. Vacuum tube 10 in Figure 5 is of the standard five prong type having filament prongs 11 and 12, a cathode prong 15, a

plate prong 14 and a grid prong 13. These prongs make contact with the receptacles in the adapter. As the combination of adapter and tube is placed in the standard tube socket the tube makes contact with all the circuits of the radio set except the grid. The grid circuit of the tube making contact with receptacle 9 does not make contact with the grid circuit of the standard tube socket as there is no prong attached at this point.

5 Terminal lugs 2 and 3 serve as in-put terminals to the tube. Terminal 3 may be grounded, if desired. Transformer 16 of a fragmentary stage of amplification preceding tube 10 consists of primary and secondary windings 17 and 18 respectively. In like manner transformer 19 shows part 15 of an amplifying stage following tube 10.

From Figure 5 it will be apparent that the adapter is a means for gaining entrance to the amplifier of a radio set and at the same time providing a means for disconnecting the apparatus ahead of the tube bearing the adapter.

20 Altho I have described a five prong vacuum tube adapter, I do not wish to be limited to the use of the same as many changes and modifications may be effected all within the scope of the 25 appended claim.

I claim:

A vacuum tube adapter for opening one of the normally closed tube input circuits of a radio receiving set and providing an input circuit connection extraneous to said receiving set circuit comprising a cup-shaped base of insulating material, a plurality of cylindrically shaped circumferentially yielding receptacles molded into the transverse portion of said base extending 35 upwardly and terminating substantially flush with the rim of the base for receiving the grid, anode, cathode and filament prongs of a vacuum tube, said anode and cathode receptacles having prong extensions protruding normally through the transverse portion of said base and adapted to be inserted in a standard tube socket of the radio receiving set, said grid receptacle terminating substantially flush with the lower portion of said base, a pair of electrical terminals 40 molded in said base and extending laterally therefrom, one of which is connected to said grid receptacle and the other to one of said filament receptacles for connecting thereto said extraneous input circuit.

HERBERT F. JERMAIN.
